(57) **CLAIM**

The ornamental design for a catheter connector, as shown and described.

DESCRIPTION

FIG. 1 is a perspective view of a catheter connector showing my new design;

FIG. 2 is a top view of the catheter connector shown in FIG. 1;

FIG. 3 is a bottom view of the catheter connector shown in FIG. 1;

FIG. 4 is a side view of the catheter connector shown in FIG. 1;

FIG. 5 is another side view of the catheter connector shown in FIG. 1;

FIG. 6 is a rear view of the catheter connector shown in FIG. 1; and,

FIG. 7 is a front view of the catheter connector shown in FIG. 1.

The circular shaped, uneven broken line in FIG. 7 represents a boundary of the claimed design. The uneven broken line representation of an aperture within the area circumscribed by the boundary, as well as the boundary itself, are for illustrative purposes only and form no part of the claimed design.
